UNITED STATES PATENT OFFICE.

SIEGFRED LESCHZINER, OF JERSEY CITY, NEW JERSEY.

EXTENSION-TABLE, &c.

SPECIFICATION forming part of Letters Patent No. 341,585, dated May 11, 1886.

Application filed May 28, 1885. Serial No. 166,912. (No model.)

To all whom it may concern:

Be it known that I, SIEGFRED LESCHZINER, a subject of the Emperor of Germany, and a resident of Jersey City, in the county of Hudson and State of New Jersey, have invented 5 certain new and useful Improvements in Furniture, of which the following is a specification.

My invention relates to an improvement in furniture, and more particularly to extension-tables, the object being to provide an article of this character which shall be simple and economical in its construction, capable of ready 10 adjustment, which shall present a neat and 15 finished appearance, and which shall be strong and durable.

My invention consists in certain novel features of construction and combinations of parts, as will be hereinafter fully described, 20 and pointed out in the claims.

In the accompanying drawings, Figure 1 is a perspective view of my improvement, showing end of table in its extended form, the top being detached therefrom. Fig. 2 is a top 25 plan view. Fig. 3 is a bottom plan view with top attached. Fig. 4 is a longitudinal section of drum, showing spring. Fig. 5 is a longitudinal vertical section. Fig. 6 shows my improvement as applied to window-shutter in 30 section.

A represents two casings or boxes, each adapted to contain a spring-actuated drum or roller, B, and supported by the legs or standards C, secured to the under side thereof. 35 The sides a of these casings A extend inwardly toward the center of the table, and have secured to their inner sides the pieces b, provided with laterally-extending lugs c.

Against the inner faces of the pieces b fit 40 the sliding pieces d, each provided with an elongated slot, e, in which fits the lug c, said pieces d being held in their proper relative positions by means of the cross-pieces f. To the forward ends of these sliding pieces d are 45 secured the inwardly-projecting lugs g, adapted to pass through and travel in the slots h, formed in the beams i, the ends of the lugs having the pegs j secured thereto for the purpose of retaining the parts in their proper 50 relative positions, and also serve for guiding the pieces d in their longitudinal movements.

To the beams i are secured the cross-pieces

k k' for the purpose of holding the beams in position, and to which former are secured the legs or standards l, and braces l', adapted to 55 support the center of the table and prevent the same from sagging. When the end of the table is pulled outwardly, the lugs c will travel in the slots e until they strike the end thereof, whereupon the sliding pieces d will also be 60 drawn outwardly, the lugs g traveling in the slot h. Any number of sliding pieces d may be used, and hence the table may be made as long as desired. This construction or frame is very simple, may be made light and strong, 65 can be extended to a great length, and when in its closed adjustment is very compact and occupies but very little room.

Within the casings A are secured the spring-actuated drums B, to which are secured the 70 ends of the top C'. The central portion, c', of this top, which extends between the two casings when the table is folded, is secured to one of the beams i, and made solid or rigid, similar to the tops of ordinary tables, but the ends 75 thereof are constructed of slats or strips c'', secured together by means of the leather strips c''' or their equivalents, thereby rendering said ends flexible and capable of being wound on the drums. The casings A extend outwardly 80 beyond the pieces a, and are each provided with a top or cover, A'. The central portion, c', of the top C' is of such width that the edges 85 will be in a straight line with the ends of the casings A; but the ends of said top are somewhat narrower for the purpose of allowing them to enter the casing and be wound on the drums. When the table is extended or drawn out the ends of the top C' will be narrower than the middle portion, the top of the 90 table thus presenting an irregular outline. To supply this deficiency, I hinge to the ends of the portion C' the strips c'', the free ends of which, when the table is in its closed adjustment, are swung up under the portion c', and 95 secured thereto by a bolt or other suitable means. When the table is extended, the strips c'' are swung around until the free ends thereof fit against the ends of the casings, the width of said strips being such that the edges of the 100 top and casings will be in a straight line. The ends of strips are secured in any desired manner to the casings A, and serve to prevent the table from returning to its closed position.

By these means the several parts composing the top of the table lie in the same horizontal plane, practically forming a solid or rigid top similar to that of ordinary tables, at the same time possessing the advantage of being flexible.

5 My improved table is very simple in its construction, can be so built that it may be extended to any length, and can be produced at a small initial cost.

10 When desired to fold the table, it is simply necessary to lower the strips c^4 , and by pushing the ends toward each other the top will fold automatically, the necessity of removing the leaves, as is the case with tables as now ordinarily constructed, being obviated.

15 My improved table-top may also be applied to shutters, gates, or doors.

20 In Fig. 6 of the drawings I have shown an improved shutter constructed in accordance with my invention. The spring roller or drum is located within the frame A^2 , and the shutter, which is constructed of small strips secured together by any desired means, is wound thereon. The shutter may be so constructed that the free end thereof may be used 25 to close the opening on the frame, and thus prevent any defacing thereof. When desired to open the shutters, the ends thereof are simply pulled outwardly, and by any convenient 30 means attached to the frame A , locked in position, and when desired to close them are simply allowed to wind around the drum.

I am aware that tables have heretofore been constructed with flexible tops, adapted, when

the table is in its closed adjustment, to be 35 folded, such construction being shown in Patent No. 278,830, granted to R. W. Tabener, June 5, 1883. I am also aware that a spring-actuated drum has been employed in connection with a flexible table-top, such being 40 shown in Patent No. 185,649, granted to J. R. Shirley, December 26, 1876, and hence I make no broad claim to such; but

45 What I claim as my invention, and desire to secure by Letters Patent, is—

1. An extension-table consisting, essentially, of the frame constructed substantially as described, casings A , secured to the ends thereof, spring rollers or drums B , secured within the casings, a rigid top, C' , secured to the frame and having its ends flexible and attached to the drums, and strips c^4 , hinged to the top and fitting against the frame for securing the parts in their proper relative positions, substantially as described.

55 2. In an extension-table, the frame consisting of the parts a , b , d , and i , of the casings A , rollers B , top C' , and strips c^4 , all combined and adapted to operate substantially as set forth.

60 Signed at New York, in the county of New York and State of New York, this 27th day of May, A. D. 1885.

SIEGFRED LESCHZINER.
